US0D1076825S

(12) **United States Design Patent** (10) Patent No.: **US D1,076,825 S**
(45) Date of Patent: ** May 27, 2025

(54) **ELECTRICAL COMPONENT BOX**

(71) Applicant: **Caterpillar Inc.**, Peoria, IL (US)

(72) Inventors: **Scott Toombs**, Daly City, CA (US);
Adam L. Berry, Raleigh, NC (US);
Ashley Dallas Menges, Clayton, NC (US);
William Clayton Martin, Stillwater, OK (US); **Ryan Pecinovsky**, Cedar Falls, IA (US)

(73) Assignee: **Caterpillar Inc.**, Peoria, IL (US)

(**) Term: **15 Years**

(21) Appl. No.: **29/839,634**

(22) Filed: **May 23, 2022**

(51) LOC (15) Cl. **13-03**

(52) U.S. Cl.

USPC **D13/152**

(57) **CLAIM**

The ornamental design for an electrical component box as shown and described.

DESCRIPTION

FIG. 1 is a perspective view of an electrical component box showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the electrical component box which form no part of the claimed design.
